UNITED STATES PATENT OFFICE.

EDWIN A. SPERRY, OF TIENSIN, CHINA.

CONCENTRATING TABLE.

Application filed October 4, 1919. Serial No. 328,458.

To all whom it may concern:

Be it known that I, EDWIN A. SPERRY, a citizen of the United States, residing at Tientsin, China, have invented certain new and useful Improvements in Concentrating Tables; and I do declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to a device for concentrating ores, and the object thereof is to provide means which will permit of motion of a concentrating table in any direction in a horizontal plane and the provision of means to transmit to the table a variety of motions, as may be desired, according to the character of the mineral handled. It is also an object of the invention to quickly classify the values on the table as they pass thereover.

Briefly, the invention comprises a rigid base above which is mounted a movable or vanning frame, supported by twisted springs of sheet metal or some similar material having sufficient elasticity. The twisted springs readily permit motion in any direction horizontally, but prevent vertical motion. A concentrating table is positioned above the vanning frame, the lower end being mounted at a single central point on the frame and the upper end being connected with the frame by adjustable means for varying the inclination of the table either transversely or longitudinally. The table is provided with grooves extending diagonally from one side, these grooves being relatively wide and deep at said side of the table and gradually decreasing in depth and width until they merge into the surface of the table on a line parallel with the sides thereof. This construction leaves one side of the table plane, and this preferably has a downward slope relatively to the plane of the table proper.

In the drawing:

Figure 1 is a plan view, indicated by line 1—1 of Figure 5.

Figure 2 is an end elevation indicated by lines 2—2 of Figures 1 and 5.

Figure 3 is a view taken on the line 3—3 of Figure 5.

Figure 4 is an enlarged elevation of one of the eccentrics.

Figure 5 is a side elevation indicated by line 5—5 of Figure 1.

Figure 6 is an end elevation from the line 6—6 of Figure 5 and showing the end opposite to that of Figure 2.

The base 10 has a plurality of vertically disposed twisted members 12, formed of sheet spring metal, secured at their lower ends thereto. The upper ends of these springs 12 are secured to the movable vanning frame 14. Two shafts 16 are located along one end and along one side of the base 10, being mounted in brackets 18. One shaft 70 carries a pulley 20 by means of which power is transmitted and bevel gears 22 transmit power to the other shaft. Each shaft carries one, two, or more, eccentrics, 24, comprising eccentric pieces 23 mounted directly on the shafts, and adjustable eccentric sleeves 25 thereabout, by means of which the stroke or throw of each eccentric may be adjusted. As shown in the drawings, a twisted sheet metal spring 26 is secured to the eccentric 24 at 124, at the end of the machine, and twisted springs 28 are secured to the eccentrics at the side of the machine, these springs 26 and 28 being similar in construction to the springs 12. The inner ends of the springs 26 and 28 are connected to blocks or beams 30 and 32 respectively, secured to the under side of the frame 14, whereby motion is transmitted to the frame. The framework 34 of the table is supported by means of straps 36, bolted thereto at the upper ends and provided at their lower ends with slots 38, adjustable upon bolts 40 for determining the inclination of the table. At the opposite end, a pin 42 projects from the framework 34 and passes through an aperture in the bracket 44, the pin being retained if desired by means of a nut 46. This pin 42 is centrally located on the lower end of the framework 34, thereby providing three points of support for the table in connection with the two adjustable straps 36. By this

55

100

construction the table may be inclined to any desired angle, both longitudinally and transversely.

The framework 34 carries a table 50, and 5 may be provided as shown at one end with a feed-hopper 52. The surface of the table is provided with a plurality of riffle grooves 54, which extend from one side of the machine diagonally across toward the other side, terminating on a line indicated at 56. These grooves opposite the line 56 are relatively deep and wide. As they extend towards the opposite side, they become gradually narrower and more shallow, until they 15 merge into the table top at the line 56. This leaves a narrow, smooth strip 58, parallel with the side of the table, which may be inclined as shown in Figure 2, relatively to the table proper in order to facilitate discharge of the values. Mounted above the 20 table is a water supply pipe 60, having branches 62 extending approximately parallel with the riffle grooves 54.

In the operation of the device, power applied through pulley 20 is transmitted by the bevel gears 22 to the shafts 16. The relative speeds of the shafts 16 may be governed by changing the relative size of the gears 22. The motion transmitted to the springs 26 25 and 28 may be varied by adjusting the eccentric sleeves 25. In this manner the stroke of one of the springs may be made longer or shorter than that of the others, and this may be further influenced by giving a variable 30 speed of rotation to the shafts 16. Thus various combinations of these features will enable the operator to produce any motion from a straight, diagonal motion, to a circular motion, as may be required for different 35 kinds of ores. It is obvious that, due to the twisted structure of the springs 26 and 28, motion in any direction perpendicular to the axis of the springs may be permitted independently of the thrust of the given 40 spring; but that the thrust transmitted to the spring will be directly transmitted to the framework due to the fact that the length of the spring is constant.

Similarly, motion in any direction in a 45 horizontal plane will be permitted by the springs 12, but vertical motion of the framework 14 will be prevented.

The inclination of the table 50 having been determined by adjusting the straps 36, and 50 the proper motion having been transmitted to the table as above described, pulp is fed thereto from the hopper 52, or from any other suitable source. The riffle grooves 54 produce classification of the mineral as it 55 passes over them; the heavier mineral being worked toward the plain strip 58, while the gangue is washed over the grooves, as is obvious. The heavier mineral will come off nearer the head of the table, and the lighter mineral, lower down. The inclination of the 60

plain strip 58 with respect to the body of the table produces a ready discharge of the minerals as soon as they leave the riffle grooves 54.

I claim:—

1. Concentrating apparatus, comprising a base, upwardly projecting springs connected at their lower ends with said base, a table-supporting frame positioned above said base, and having the upper ends of said springs 70 connected thereto, whereby said springs support said frame, means to impart horizontal movement to said frame, comprising twisted metal spring straps connected to said frame, and eccentrics connected with said straps to reciprocate the same, certain of said eccentrics being positioned at one side of the frame, and certain of said eccentrics and straps being positioned at one end of the frame. 75

2. Concentrating apparatus comprising a base, upwardly projecting springs connected at their lower ends with said base, a table supporting frame positioned above said base and having the upper ends of said springs 90 connected thereto, whereby said springs support said frame, means to impart horizontal movement to said frame, comprising straps connected to said frame and eccentrics connected with said straps to reciprocate the same, certain of said eccentrics being positioned at one side of the frame and certain of said eccentrics being positioned at the adjacent end of the frame, whereby motion may be produced in a direction other than in the 95 direction of the length or breadth of the frame and table and means for adjusting the throw of said eccentrics. 100

3. Concentrating apparatus, comprising a base, upwardly projecting twisted spring straps connected at their lower ends with said base, a table-supporting frame positioned above said base and having the upper ends of said spring straps connected therewith, horizontally-extending spring straps 105 also connected with said frame, certain of said horizontal straps extending in one direction and certain thereof extending in another direction, and means to reciprocate said horizontal straps. 110

4. Operating mechanism for concentrating tables, comprising in combination with the table a support therefor, comprising means for permitting horizontal movement in all directions, and means for simultaneously imparting to the table reciprocating movement in both longitudinal and transverse directions, including means for varying the degree of longitudinal reciprocation at different points along the end of the table. 115

5. Operating mechanism for concentrating tables, comprising in combination with the table a support therefor, comprising means for permitting horizontal movement in all directions, and means for simultane- 120

ously imparting to the table reciprocating movement in both longitudinal and transverse directions, including means for varying the degree of transverse reciprocation at 5 different points along the side of the table.

6. Operating mechanism for concentrating tables, comprising in combination with the table a support therefor, comprising means for permitting horizontal movement 10 in all directions, and means for simultaneously imparting to the table reciprocating movement in both longitudinal and transverse directions, including means for varying the degree of reciprocation in both directions at different points along the end and side of the table.

7. Operating mechanism for concentrating tables, comprising in combination with the table a frame upon which the latter is 20 mounted, a support for the frame comprising means for permitting horizontal movement in all directions, and means for simultaneously imparting to the said frame reciprocating movement in both longitudinal and transverse directions, including means for varying the degree of longitudinal reciprocation at different points along the end of the frame.

8. Operating mechanism for concentrating tables, comprising in combination with the table a frame upon which the latter is 30 mounted, a support for the frame comprising means for permitting horizontal movement in all directions, and means for simultaneously imparting to the said frame reciprocating movement in both longitudinal and transverse directions, including means for varying the degree of transverse reciprocation at different points along the side of the 35 frame.

9. Operating mechanism for concentrating tables, comprising in combination with the table a frame upon which the latter is 45 mounted, a support for the frame comprising means for permitting horizontal movement in all directions, and means for simultaneously imparting to the said frame reciprocating movement in both longitudinal and transverse directions, including means for varying the degree of reciprocation in both 50 directions at different points along the end and side of the frame.

10. Operating mechanism for concentrating tables, comprising in combination with the table a horizontally disposed frame upon 55 which the table is mounted, a support for the frame comprising means for permitting horizontal movement in all directions, and means for simultaneously imparting to the frame reciprocating movement in both longitudinal and transverse directions, including means for varying the degree of longitudinal reciprocation at different points along the end of the frame.

65 11. Operating mechanism for concentrat-

ing tables, comprising in combination with the table a horizontally disposed frame upon which the table is mounted, a support for the frame comprising means for permitting horizontal movement in all directions, and 70 means for simultaneously imparting to the frame reciprocating movement in both longitudinal and transverse directions, including means for varying the degree of transverse reciprocation at different points along 75 the side of the frame.

12. Operating mechanism for concentrating tables, comprising in combination with the table a horizontally disposed frame upon which the table is mounted, a support for 80 the frame comprising means for permitting horizontal movement in all directions, and means for simultaneously imparting to the frame reciprocating movement in both longitudinal and transverse directions, including 85 means for varying the degree of reciprocation in both directions at different points along the end and side of the frame.

13. Operating mechanism for concentrating tables, comprising in combination with the table a frame a support for the frame comprising means for permitting horizontal movement in all directions, means for supporting the table on said frame in a longitudinally inclined position, and means for 90 simultaneously imparting to the frame reciprocating movement in both longitudinal and transverse directions, including means for varying the degree of longitudinal reciprocation at different points along the end 100 of the frame.

14. Operating mechanism for concentrating tables, comprising in combination with the table a frame a support for the frame comprising means for permitting horizontal 105 movement in all directions, means for supporting the table on said frame in a longitudinally inclined position, and means for simultaneously imparting to the frame reciprocating movement in both longitudinal 110 and transverse directions, including means for varying the degree of transverse reciprocation at different points along the side of the frame.

15. Operating mechanism for concentrating tables, comprising in combination with the table a frame a support for the frame comprising means for permitting horizontal movement in all directions, means for supporting the tables on said frame in a longitudinally inclined position, and means for 120 simultaneously imparting to the frame reciprocating movement in both longitudinal and transverse directions, including means for varying the degree of reciprocation in 125 both directions at different points along the end and side of the frame.

16. Operating mechanism for concentrating tables, comprising in combination with the table a frame a support for the frame 130

comprising means for permitting horizontal movement in all directions, means for adjusting the table on the frame to give it both longitudinal and transverse inclination, 5 and means for simultaneously imparting to the table reciprocating movement in both longitudinal and transverse directions, including means for varying the degree of longitudinal reciprocation at different 10 points along the end of the frame.

17. Operating mechanism for concentrating tables, comprising in combination with the table a frame, a support for the frame comprising means for permitting horizontal 15 movement in all directions, means for adjusting the table on the frame to give it both longitudinal and transverse inclination, and means for simultaneously imparting to the table reciprocating movement in

both longitudinal and transverse directions, 20 including means for varying the degree of transverse reciprocation at different points along the side of the frame.

18. Operating mechanism for concentrating tables, comprising in combination with the table a frame, means for adjusting the table on the frame to give it both longitudinal and transverse inclination, and means for simultaneously imparting to the table reciprocating movement in both longitudinal and transverse directions, including means for varying the degree of reciprocation in both directions at different points along both the end and side of the frame.

In testimony whereof I affix my signature.

EDWIN A. SPERRY.
